UNITED STATES PATENT OFFICE.

ALBERT E. ZIMMER, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP CAR.

Application filed March 28, 1923. Serial No. 628,177.

To all whom it may concern:

Be it known that I, ALBERT E. ZIMMER, a citizen of the United States, residing at Chicago, in the county of Cook and State 5 of Illinois, have invented a certain new and useful Improvement in Dump Cars, of which the following is a full, clear, concise, and exact description, reference being had to the accompanying drawings, forming a 10 part of this specification.

This invention relates to improvements in dump cars and primarily to ballast cars of the convertible type adapted to discharge the lading through the bottom or the sides 15 thereof.

In cars of the identified type, adapted to discharge lading at the sides of the track, it has heretofore been customary to employ heavy sills in the underframe to carry the 20 load between bolsters or else form the sides of trusses and dispose dumping doors in the floor of the car through which the lading is discharged. Both of said methods have 25 disadvantages, inasmuch as in the case where the load is carried by sills formed in the underframe, the weight of the empty car is found to be excessive and, whereas this defect is partially eliminated when the 30 load is carried through the medium of trussed sides, it has been found that the dumping area provided by the floor doors is inadequate for efficient discharge of the lading.

The object of my invention is to provide, 35 a car of the type indicated, wherein the side walls act as load carrying members, and are so constructed as to retain the great strength required and still have large dumping openings formed therein, the extreme depth of the sides being utilized for 40 this purpose thereby securing strength combined with light weight.

I have found that the most economical method of carrying out my invention is to 45 dispose the discharge doors intermediate the tension and compression chords of a girder with the vertical members of the girder disposed between the doors.

My invention resides, further, in the 50 novel construction and arrangement of parts, such as will be apparent from the following description and drawings, and which will be more particularly pointed out in the appended claims.

In the drawings forming a part of the

specification, Fig. 1 is a side elevational view of slightly more than half the side of a car embodying my improved construction. Fig. 2 is a sectional, plan view of a portion of the underframe corresponding substantially to the line 2—2 of Fig. 1. Fig. 3 is a vertical, transverse, sectional view corresponding substantially to line 3—3 of Fig. 1. Fig. 4 is a side elevational view of slightly more than one half of the side of a car, illustrating a modification of my invention. Fig. 5 is a vertical, transverse, sectional view taken through one of the sides of the car, on a line corresponding substantially to the line 5—5 of Fig. 4. Fig. 6 is a horizontal, sectional view taken through one of the upright members, corresponding substantially to the line 6—6 of Fig. 4.

In said drawings and referring first to 75 Figs. 1 to 3, showing the preferred form of the invention, the improved car is shown as having built up sides A—A with side doors B hinged thereto; a single built up center sill C; fixed longitudinally extending 80 side floor sections D; pivoted floor doors E, movable to form either the inclined side walls of a central discharge hopper, or part of a level floor gondola car; and pivoted hopper doors F. The car is suitably tied 85 together by means of end sills G, body bolsters H, crossbeams J, and preferably permanent ends K. The center sill C is preferably formed of I section extended from end sill to end sill, and fitted near the ends 90 thereof with suitable draft sills L. Extending from a point near the junction of the end sill and draft sill to the junction of the body bolster and side sill on each side of the car are horizontally disposed diagonal 95 braces M.

The sides A of the car, in the preferred form, each consist of upper and lower chords, the upper chord, in this instance, consisting of a web plate 10 having the upper margin reinforced by a bulb angle 11, and the lower chord, preferably, consisting of a web plate 12 having the upper and lower margins thereof, respectively, reinforced by angle members 13 and 14 which 100 are preferably so disposed as to have the horizontal flanges extending inwardly towards the center of car, said upper flange 13 also forming a support for the fixed side floor section D. Intermediate said upper 105

and lower chords are hinged doors B, preferably, numbering six to one side of a car.

The discharge openings in the sides are provided by suitably spacing the upper and lower chords from each other in a vertical direction, such vertical spacing being maintained by vertically extending members, which, at the ends of the car, consist of corner posts 15 and intermediately of the ends of the car comprise, a series of posts 16, which are preferably formed of I-beam section, said posts 16 being further strengthened by means of gusset members 17 each secured to the upper chord, lower chord and posts respectively, and disposed on either side thereof. The gusset members preferably consist of flat plates rigidified by having a vertically disposed corrugation 17^a formed therein. The lower margin of the upper chord is rigidified by means of stiffener angles 18 which are riveted to the web plates 10, and extend between the posts. The angles 18 are preferably crimped to extend over the inner flange of the I-beam posts 16 and are riveted thereto. Hinge brackets 19 are riveted to both flanges of the stiffener angles 18 and the dumping doors B are pivotally mounted thereon.

The corner posts 15 are formed of sufficient width to accommodate the safety appliances required by law, and in this instance a ladder is shown, comprising, grab irons 20 and a sill step 21. The corner post is preferably formed of a plate bent at right angles with a flange 21 forming a portion of the end of the car, having the lower portion thereof secured to the end sill G, while at the top thereof, connection is made with a transversely extending member 22, preferably a bulb angle; the end sills and top members thus effectively spacing the side members at the top and bottom thereof and tending to maintain the same in vertical alinement in order that they may adequately fulfill their function as load carrying members. The corner posts are further stiffened by vertically disposed angles 23 which are spaced from the end wall of the car a sufficient distance to provide a storage space for boards which are utilized to form the ends of the central hopper when the car is used as a center dump hopper ballast car.

In the particular type of side construction illustrated in Fig. 1, it will be noted that the load carrying vertical members at the ends of the car are at opposite sides of the bolsters to provide door openings of generous proportions at each end of the car. Such a construction would ordinarily place the lower chord on the side intermediate the body bolster and the first vertical member of the side under a bending strain and in order to relieve such lower chord of undue bending strain I have made provision for the center sill to sustain a proportion of the

strain, transferring such proportion of the strain to the sides through the crossbeams J which are preferably secured to the sides adjacent each vertical member and also secured to the latter.

Any suitable side door construction may be used, but the preferred form is that indicated in the drawings, consisting of a plurality of side boards 24, united by hinge angles 25, formed at the upper ends thereof with hinge eyes 26, the lower ends of the hinge angles being extended below the lower margin of the door and below the floor level of the car, thereby presenting abutments 27 which are adapted to be engaged by pivoted latches 28 to maintain the doors in closed position. Said latches 28 are movable in slotted brackets 29 secured to the lower chord of the car sides, two latches per door being generally used for doors of the average size, each pair of latches 28 being preferably connected by a bar 30 sliding in brackets 31. One of the latches is provided with a downwardly extending handle 32 whereby the latches are operated and a locking cam 33 is engageable with the latch portion of the handle carrying latch to guard against unlocking movement of both latches.

I am aware that cars have heretofore been constructed with side doors hinged to a top rail carried on stakes secured to a longitudinal sill in the underframe, but in such construction no attempt has been made to cause the top rail to cooperate with the sill in the underframe inasmuch as the sectional area of the top rail has not balanced that of the underframe side sill, nor have the vertical members or stakes been of adequate strength or their disposition in the car structure such as to permit of their carrying the vertical load. In my improved construction, however, I have utilized the full depth of the side as a beam, by attaching the upper and lower chords thereof to the vertical members in such a manner that one chord will be in tension and the other in compression.

In Figs. 4 to 6, I have shown a modified construction, wherein, the dumping door openings in the side are disposed only from bolster to bolster, only one half of the side of the car being shown. In said drawings, 100 designates the bolster, 101 designates the web of the upper chord, 102 the web of the lower chord, 103 the end panel, 104 the corner band, 105 the side top stiffening member, 106 the outer vertical stakes, 107 inner vertical stakes, 108 vertical gusset members, 109 horizontal stiffeners for the lower margin of the upper chord, 110 the upper stiffening member of the lower chord. The stiffening means for the lower margin of the lower chord, in this instance is preferably formed of a plurality of sections 111 and 112 disposed in an overlapping relation, with the

section of the side over the trucks formed of restricted depth. While I have shown the lower stiffening of the lower chord in separate sections, it will be evident that the same result may be attained by bending the angle and forming the side of fishbelly construction.

Suitable operating mechanism for the hopper doors, forming no part of the present invention, however, is carried on the side of the car as indicated at 113. In the illustration in Fig. 4, the side dumping doors are omitted for the purpose of clearness, but it will be understood that such doors are provided, being pivotally mounted on the hinge brackets 114. Side ladders to meet the safety appliance requirements are provided by means of grab handles 115, which are secured to the end panels, and sill steps 116 which are secured to the lower chords of the side in alignment with the grab handles. Extending from the bolster to the end of the car reinforcing angles 117 stiffen the end panel longitudinally and provide a support for the floor 118.

The provision of inner and outer stakes in the manner illustrated provides for vertical posts of great strength and rigidity, and furthermore permits the anchoring of the sides to the underframe in a very secure manner, maintaining the sides in a vertical plane and permitting the same to fulfill their functions as load carrying members in a most effective manner.

By my improved side construction I effect important economies in manufacture, inasmuch, as great strength is secured with light weight due to the extreme depth of the side members.

While I have shown composite constructions which are the preferred embodiments of my invention, it is to be understood that the side may be constructed of a sheet of metal and the door openings formed therein in the nature of perforations, thereby, eliminating a considerable number of rivets.

I have shown and described what I now consider the preferred embodiments of my invention, but the same are merely illustrative and I contemplate all changes and modifications that come within the scope of the claims appended hereto.

What I claim is:

1. In a side element for railway cars, the combination with an upper load carrying chord comprising a plate of extended depth disposed edgewise to the load; of a lower load carrying chord of similar construction, said chords being spaced apart to provide a dumping opening therebetween; a plurality of spaced members between said upper and lower chords, said spaced members being rigidly secured to the chords respectively, said chords and spacing members together constituting a single rigid structure; and

dumping doors adapted to close the dumping space.

2. In a railway car side element constituting a load carrying member; the combination with upper and lower chords, said chords being spaced apart to provide a dumping space therebetween; of vertical spacing members secured to the said upper and lower chords; and gusset members between said vertical members and chord members.

3. In a railway car side element constituting a load carrying member, the combination with upper and lower chords spaced apart to provide a dumping space therebetween; vertical members extending between the upper and lower chords and spaced apart to provide a plurality of dumping openings; reinforcing members on the lower margin of the upper chord and the upper margin of the lower chord; and gusset plates disposed on either side of the vertically extending members, said plates being secured to the vertically extending members and the reinforced margins of the upper and lower chords.

4. In a railway car, the combination with side walls; of a floor; an underframe including a relatively deep center sill; body bolsters and diaphragms extending between the side walls and center sill, said side walls being formed of upper and lower load carrying chords spaced apart to provide dumping spaces therebetween, each of said chords being in the form of a web plate of extended depth disposed edgewise to the load, and vertical members rigidly connecting said upper and lower chords.

5. In a railway car, the combination with a center sill and body bolsters; of side walls adapted to transmit load from bolster to bolster, said side walls comprising upper and lower chords spaced apart to provide dumping spaces therebetween, each of said chords being in the form of a web plate of extended depth disposed edgewise to the load, and vertical members rigidly connecting said upper and lower chords, said chords and vertical members together constituting a single beam; dumping doors hinged to the upper chord intermediate the vertical members; and crossbeams extending between the vertical members of the side walls and the center sill.

6. In a railway car, having an underframe including a center sill adapted to transmit draft and buffing strains, the combination with side elements, each of which comprises a web plate of extended depth disposed edgewise to the load and provided adjacent its margins with angularly disposed flanges; of crossbearers connecting the center sill and side elements, said side elements having upper and lower chords spaced apart to provide dumping spaces

therebetween, said upper and lower members being united by vertical members to form a single load carrying element; and doors pivotally mounted on the upper chord and disposed intermediate of the vertical members.

7. In a railway car side adapted to act as a beam, the combination with corner posts at each end of the car; of upper and lower chord members extending between the said posts and spaced in a vertical direction from each other to provide dumping space; vertical members connected to each of said chords; gusset members connected to the vertical members and to the chord members; a continuous stiffening member extending along the upper margin of the upper chord; short stiffening members extending along the lower margin of the upper chord between the vertical posts; stiffening members secured to the respective margins of the lower chord; and dumping doors hinged to the upper chord.

8. In a railway car, the combination with end elements and body bolsters; of side elements comprising corner members disposed within the space between the ends of the car to the body bolsters, upper and

lower chords extending from said corner members, each of said chords being in the form of a web plate of extended depth having angularly disposed flanges along its margins, said chords being spaced apart in a vertical direction to provide dumping space between the said chords, and vertical members connecting said upper and lower chords and dividing the sides of the car into a plurality of openings; and doors to close said dumping openings.

9. In a side element of railway cars, the combination with an upper load carrying chord comprising a plate of extended depth disposed edgewise to the load, said web plate having flanges on its margins angularly disposed with reference to the web plate; of a lower load carrying chord of similar construction, said chord being spaced apart to provide a dumping opening therebetween; of a plurality of spaced connecting members; and dumping doors adapted to close the dumping space.

In witness that I claim the foregoing, I have hereunto subscribed my name this 26th day of March, 1923.

ALBERT E. ZIMMER.
